United States Patent Office

Des. 221,184
Patented July 13, 1971

221,184

VENDING MACHINE

Wayne C. Cathey, Dallas, Tex., assignor to Burger Chef Systems, Inc., Indianapolis, Ind.

Filed Apr. 7, 1970, Ser. No. 22,310

Term of patent 14 years

Int. Cl. D20—01

U.S. Cl. D52—3

FIG. 1

FIG. 2

FIG. 1 is a perspective view of a vending machine showing my new design; and

FIG. 2 is an elevational view of the side thereof, opposite to the side shown in FIG. 1.

The top and rear of the vending machine are substantially plain and unornamented.

I claim:

The ornamental design for a vending machine, as shown and described.
